COVER FOR GARMENT HANGERS

Myron B. Gwinn and Donald E. Hopkin,
Denver, Colo.

Application May 11, 1950, Serial No. 161,324

3 Claims. (Cl. 223—98)

1

This invention relates to protective covers for garment hangers and the like, and more particularly to a protective cover for the conventional light-weight wire-formed garment hangers commonly used in cleaning and dry goods establishments, and has as an object to provide a cover adapted to enclose the body of a garment hanger and thereby prevent contact of said hanger with articles draped thereover.

A further object of the invention is to provide a cover which shall snugly contain the hanger and which shall cover all of the members thereof without gripping any single member and which, when containing the hanger, shall bulge or round outwardly over and on each side of the hanger arms.

Another object of this invention is to provide a cover which will snugly contain a garment hanger without gripping any particular member of the hanger, thereby permitting flexure of the hanger members within the cover, such flexure commonly occurring by loading the hanger with a garment.

Yet another object of this invention is to provide a garment hanger cover adapted to be manufactured out of paper sheet material obtainable in the form of rolls of ribbon which has the opposite sides of opposite margins stripped with a latex-type adhesive, such roll material being a commercial low-cost product, whereby said garment hanger cover may be produced at an extremely small unit cost.

Another object of this invention is to provide a garment hanger cover adapted to be manufactured out of paper sheet material in the form of rolls of ribbon having the opposite sides of the opposite margins stripped with a latex-type adhesive, such manufacture consisting of cutting simple blanks from said ribbon material.

Another object of this invention is to provide a garment hanger cover which may be conveniently supplied in the form of paper blanks cut from ribbon material having the opposite sides of its opposite margins stripped with a latex-type adhesive, said blanks being adapted to be compactly stacked and packaged, and further adapted to be folded about a garment hanger by quick, simple manual movements.

Another object of this invention is to provide a garment hanger cover formed as a paper blank adapted to be folded over a garment hanger having, when folded, a convenient opening to its interior portion wherein identification or data bearing cards or other similar light-weight objects may be placed.

2

With these and other objects in view, all of which shall hereinafter more fully appear, our invention comprises certain new and novel constructions, arrangements and combinations of elements as hereinafter described and as defined in the appended claims, and illustrated, in preferred embodiment, in the accompanying drawing in which:

10 Figure 1 is an illustration, somewhat diagrammatic in nature, of a roll of paper ribbon material prepared with marginal strips of adhesive adapted for use in the present invention.

15 Figure 2 illustrates, on a considerably enlarged scale, a blank cut from the strip material illustrated at Fig. 1, with a conventional garment hanger placed thereon as in position for folding.

20 Figure 3 illustrates the blank as partially folded over the garment hanger with portions of the blank indicating various intermediate positions in the folding process.

25 Figure 4 illustrates the folded cover enclosing a garment hanger with a card inserted in the inner portion to further illustrate the use and nature of construction of the cover.

Figure 5 is a section, on a further enlarged scale, as taken on the indicated line 5—5 at Fig. 4.

30 Figure 6 illustrates a blank positioned for folding over a hanger with the garment hanger placed over the blank and with the fingers of the operator positioned for gripping the blank and hanger as in an initial step of the folding operation.

35 Figure 7 is similar to Fig. 6 illustrating the blank partially folded over the hanger by manipulation of the thumb.

Figure 8 is similar to Figs. 6 and 7 illustrating the further folding of the blank by the fingers to enclose the garment hanger therein.

With the present extensive development of latex-type adhesive, it is now possible to apply adhesive coatings to material such as paper which will not adhere to any surface other than a similar latex-coated surface but will be tightly and instantly joined to such similar surface by simply pressing the parts together. In the preparation of paper blanks for subsequent folding or other manipulation, it is possible to stack or pile a large number of paper blanks having adhesive-prepared surfaces together without any undesirable sticking, provided that the prepared surfaces are arranged so as not to contact each other while stacked. With such an arrangement certain advantageous constructions of paper articles are possible which permit cheap manufacture and compact storage and packaging of the blanks prior to folding or other similar final steps in

preparation for their use, it being anticipated that such final steps involve the joining of the adhesive-prepared surfaces.

A conventional way of providing commercially, in quantity, a prepared adhesive-coated paper adapted for various uses, is with a ribbon having adhesive-coated strips at the opposite sides of the opposite margins. In a paper ribbon 9 adapted for the present invention the adhesive-coated strips 11 and 11a at the opposite sides 10 and 10a of the opposite margins 12 and 12a cannot contact any adhesive-prepared surface to cause sticking, for such ribbon is generally supplied as rolls R, and, when rolled, the adhesive strips always contact a clean paper surface of the adjacent paper. In preparation of such a roll for the present invention it is also desirable to provide a folding crease 13 therein suitably marked in spaced parallelism with the edge of the ribbon. Such prepared ribbon, in the form of rolls R, is a low-cost, conventional item, and the garment hanger cover, embodying the present invention is designed to be made of the above-described ribbon material with a minimum of further steps in the preparation of a cover blank 14.

In the present invention the blank 14 is cut from a suitable length of paper ribbon material 10. This material has comparatively narrow oppositely faced adhesive strips 11 and 11a adjacent the respective margins 12 and 12a with the folding crease 13 along the inner edge of the adhesive strip 11. The width of the ribbon material between the margins 12 and 12a is somewhat greater than the height of the body of a conventional hanger H, enough so that the effective width after folding at the crease 13 is approximately the same as the height of the body of the hanger H. The length of the blank 14 is approximately equal to the span of the outstanding arms 15 of the hanger although this length may be varied somewhat if desired.

The opposite ends of the blank are symmetrically formed with the lower edge, which carries the adhesive-coated strip 11, having its corners suitably clipped as at 16 and the upper corners of the blank being clipped as at 17, directed inwardly from a point a short distance above the crease 13 to the margin 12a, the slope 17 being so disposed as to lie in substantial parallelism with the crease 13 and adjacent thereto upon being folded over the arms 15 of the garment hanger as hereinafter described. At the top center of the blank there is provided a notch 18 which is cut to assist the proper positioning of the hanger H upon the blank, the base of the hooked portion 19 of the hanger being suitably positioned at said notch.

It is to be seen that this blank 14 may be cut from ribbon material to the proper length and shape by any suitable knife means, which, by well-known means, may be arranged to a continuous cutting and preparation of the blanks as the ribbon is unrolled. Such blanks are suitable to receive printed matter thereon, as for advertising, which may be applied either to the ribbon or to the blanks after they are cut. With the construction herein provided it is convenient to stack a plurality of the blanks 14 to provide a compact package which may be shipped or stored and used later as needed. The adhesive coated edges lie against adjacent clean surfaces when stacked in a symmetrical manner and no blank will tend to stick to the adjacent blanks.

In the use of such blanks to form the cover a

hanger H is suitably positioned on the face 10a with the lower bar 20 of the hanger adjacent the crease 13 and with the base of the hook 19 at the notch 18 as clearly illustrated at Figs. 2 and 6.

As a first step in covering the hanger, the marginal portion below the crease 13 is folded upwardly over the bar 20 to expose the adhesive strip 11 as illustrated at Figs. 3, 4, 7 and 8. The second step is to fold the portions of the blank, which extend outwardly and above the arms 15 of the hanger, over said arms to position the sloping edges 17 in spaced parallelism and adjacent the crease 13 as clearly illustrated at Figs. 3 and 8. With such folding operation a portion of the adhesive strip 11a contacts a portion of the adhesive strip 11 adjacent the base of the cover to thereby connect the paper surfaces at area 21 which is indicated in broken lines at Figs. 3 and 8. This step completes the enclosure of the hanger within the cover. So enclosed, the hanger is snugly encased by the cover; yet no individual member thereof is actually gripped. The material forming the blank has a certain amount of resiliency and it is not stretched taut in the applying operation. This results in a slight bulging of the material on each side of the arms, thus forming a gently rounded surface over the arms instead of a sharp edge such as would be formed were the material gripped snugly around each arm. This result is most advantageous in preventing the creasing of filmy garments hung on the covered hanger. The individual members of the hanger are free to flex within the cover to a certain degree whenever the hanger is loaded as by placing a garment thereon.

It is to be noted that the portion of the adhesive-coated strip 11a adjacent the hook 19 appears to fold over itself. However, the conventional hanger at this base of the hook 19 is formed with short horizontal extensions 22 of the arms 15 between the base of the hook and the sloping portion of the arms. It follows that the adhesive strip 11a at said overlapping points adjacent the base of the hook 19 is effectively held apart by such hanger construction and the elements of the blank are so positioned and proportioned that no sticking of the latex surface 11b upon itself will occur.

In the folded position of the blank enclosing the hanger, the interior portion defined by the folds of the blank over the arms 15 to join the edge 17 with the upfolded strip at the base may be used as pockets which may be used to contain small lightweight articles such as identification card 23, the access to the pockets being at the sloping edges 12a of the folded cover. This construction is especially desirable in drygoods articles where it is necessary to have identification cards, statements, etc. with the hanger.

The application of a number of covers to hangers may be accomplished by suitable mechanical devices or may be done manually, in either case the operations performed being of a similar nature. Figs. 6, 7 and 8 illustrate one method of the manual application of a cover to a hanger, these steps being exceedingly simple in nature. A blank 14 may be positioned with the face 10a upwardly. As a first step the hanger H will be placed in position and held thereto by placing the index fingers upon the arms 15. The margin 12 is then contacted by the thumbs and folded upward and over the bar 20 of the hanger and the thumb pressure then holds the hanger in position by contacting the lower bar through

the folded margin. As this movement is completed the sloping edges 17 are contacted by the middle finger and lifted and folded over the arms 15. As the middle finger lifts the edges of the blank, the index finger likewise supplements the movement of middle finger, and as the fold over the arms 15 is completed, the index finger is extended centrally toward the area 21 whereby the pressure at the overlapping portions of strips 11 and 11a are pressed together and adhere to 10 each other, and the operation is completed. With such simple movements it is apparent that a large number of hangers may be covered manually in a very short time.

While we have herein described a preferred construction of our invention, alternatives and equivalents will occur to those skilled in the art which are within the scope and spirit of our invention; therefore, we desire that our protection be limited only by proper spirit and scope 20 of the appended claims.

We claim:

1. A blank for formation of a cover for a conventional wire garment hanger having a horizontal bar and shoulder bars upwardly converging therefrom, said blank having parallel top and bottom edges, a marginal coating of adhesive along each of said edges but on respectively opposite faces of the blank, the adhesive having the characteristic of adhering to a like coated surface but of non-adherence to an uncoated surface, a body portion of said blank having an area at least as large as the area of said hanger within the outer lines of said bars, one of said coated margins being adapted to fold upwardly 35 over said horizontal bar and thereby outwardly expose said coated margin, the upper corner portions of said blank being adapted to fold downwardly over said shoulder bars and thereby to bring portions of said oppositely coated margin into engaging contact with said outwardly

exposed coated margin, the body of said blank, within said horizontal bar and said shoulder bars, being uncoated whereby to avoid adherence of the folded portions of said blank with the body portion thereof.

2. A cover for a conventional wire garment hanger having a horizontal bar and shoulder bars upwardly converging from the horizontal bar, said cover being formed of paper-like material and having a body portion overlying one side of the hanger, flaps integral with said body portion but projecting respectively beyond and being respectively folded over said horizontal bar and said shoulder bars, the flap folded over the horizontal bar being coated, on its face which is outwardly exposed when folded, with an adhesive having the characteristic of adherence to a like coated surface but non-adherence to an uncoated surface, the flaps folded over the shoulder bars overlapping said first folded flap and being coated with like adhesive at such overlapping areas, the body portion being uncoated in the area within said bars whereby to avoid adherence between the flaps and the body portion.

25 3. In a cover as defined in claim 2, the edges of said shoulder-bar flaps nearest the center of the cover being spaced apart whereby to provide an opening for insertion of an article therethrough and into the space between the flaps and the body portion.
